[57] CLAIM

The ornamental design for a fluid dispenser, as shown and described.

DESCRIPTION

FIG. 1 is a perspective view of the preferred embodiment of the invention;

FIG. 2 is a left side view of FIG. 1;

FIG. 3 is a top view of FIG. 1;

FIG. 4 is front view of FIG. 1;

FIG. 5 is a rear view of FIG. 1;

FIG. 6 is a bottom view of FIG. 1;

FIG. 7 is a front view of another embodiment of the fluid dispenser;

FIG. 8 is a top view of FIG. 7;

FIG. 9 is a bottom view of FIG. 7; and,

FIG. 10 is a rear view of FIG. 7, the front views being the same as FIG. 4.

The broken line showing of a trigger is for illustrative purposes only and forms no part of the claimed design.
